US00D757171S

(12) **United States Design Patent**
Kim et al.

(10) **Patent No.:** US D757,171 S
(45) **Date of Patent:** ** May 24, 2016

(54) **PRINTER**

(71) Applicant: **Samsung Electronics Co., Ltd.**,
Suwon-si (KR)

(72) Inventors: **Kyong-Hwan Kim**, Seoul (KR);
Seungwook Jeong, Seoul (KR);
Taekung Park, Seoul (KR)

(73) Assignee: **Samsung Electronics Co., Ltd.**,
Suwon-si (KR)

(**) Term: **14 Years**

(21) Appl. No.: **29/485,283**

(22) Filed: **Mar. 18, 2014**

(30) **Foreign Application Priority Data**

Sep. 26, 2013 (KR) 30-2013-0049125

(51) **LOC (10) Cl.** **14-02**

(52) **U.S. Cl.**
USPC **D18/55**

(58) **Field of Classification Search**

USPC D18/36-39, 50, 53.54, 54.1, 55, 53;
D14/420-425, 462-470; 400/613,
400/613.1-613.4, 690.1-690.4, 691-694

(57) **CLAIM**

We claim the ornamental design for a printer, as shown and described.

DESCRIPTION

FIG. 1 is a front perspective view of a printer showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a front perspective view of a second embodiment of FIG. 1.

The broken lines depict environmental subject matter, are for illustration only and form no part of the claimed design.

1 Claim, 8 Drawing Sheets

FIG. 1

FIG. 2

FIG.3

FIG.4

FIG.5

FIG.6

FIG. 7

FIG. 8
